PLASTIC LENS-LOUVER

Jack G. High, Winfield, Ill., assignor to MSL Industries,
a corporation of Minnesota

Filed Oct. 18, 1965, Ser. No. 87,562

Term of patent 14 years

(Cl. D48—16)

Fig. 1

Fig. 2

FIGURE 1 is a photographic reproduction representing a fragmentary top perspective view of a plastic lens-louver embodying my new design;

FIG. 2 is a photographic reproduction representing a fragmentary underneath view of the plastic lens-louver of FIG. 1;

FIG. 3 is a fragmentary bottom plan view of the lens louver of FIG. 1;

FIG. 4 is a fragmentary top plan view of the lens louver of FIG. 1;

FIG. 5 is a fragmentary sectional view taken on the line 5-5 of FIG. 4, with midwidth portions thereof removed; and

FIG. 6 is a fragmentary sectional view taken on the line 6-6 of FIG. 4 with midwidth portions thereof removed.

I claim:
The ornamental design for a plastic lens-louver, substantially as shown and described.
